UNITED STATES PATENT OFFICE.

LOUIS NITSCHE, OF JOHNSONBURG, PENNSYLVANIA.

DESIGN FOR A STAND OR PEDESTAL.

49,314.

Specification for Design.

Patented July 4, 1916.

Application filed May 11, 1916. Serial No. 96,930. Term of patent 14 years.

To all whom it may concern:

Be it known that I, LOUIS NITSCHE, a citizen of the United States, residing at Johnsonburg, in the county of Elk and State of Pennsylvania, have invented a new, original, and ornamental Design for a Stand or Pedestal, of which the following is a specification, reference being had to the accompanying drawing, forming part thereof.

Figure 1 is a front elevation of the stand

or pedestal, showing my new design. Fig. 2 is a plan view thereof.

I claim:—

The ornamental design for a stand or pedestal, as shown.

LOUIS NITSCHE.

Witnesses:

GEO. G. HOH,
THOS. SWEENEY.
